(57) **CLAIM**

The ornamental design for a broom and dustpan set, as shown and described.

DESCRIPTION

FIG. 1 is a perspective view of the broom showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of a portion indicated with numeric 8 in FIG. 1;

FIG. 9 is a perspective view of the dustpan showing my new design;

FIG. 10 is a perspective view of FIG. 9 from another angle;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a top plan view of FIG. 9;

FIG. 16 is a bottom plan view of FIG. 9;

FIG. 17 is an enlarged view of a portion indicated with numeric 17 in FIG. 9;

FIG. 18 is a perspective and assembled view of the broom and dustpan set;

FIG. 19 is a perspective view of the broom and dustpan set when in use;

FIG. 20 is a perspective view from another angle of FIG. 19; and,

FIG. 21 is a perspective and assembled view of the broom and dustpan set from a different angle.

The broken lines shown in the drawings are included for the purpose of illustrating portions of the broom and dustpan set that form no part of the claimed design.

1 Claim, 21 Drawing Sheets
